INVENTOR

UNITED STATES PATENT OFFICE

100,979

DESIGN FOR A BLOUSE

Greta Baum, New York, N. Y.

Application July 29, 1936, Serial No. 64,125

Term of patent 3½ years

To all whom it may concern:

Be it known that I, Greta Baum, a citizen of the United States of America, residing in Manhattan, county of New York and State of New York, have invented a new, original, and ornamental Design for a Blouse, of which the following is a specification, reference being had to the accompanying drawing, forming part thereof, wherein,

I claim:

The ornamental design for a blouse, substantially as shown.

GRETA BAUM.
